UNITED STATES PATENT OFFICE.

DON J. COOK, OF KALAMAZOO, MICHIGAN, ASSIGNOR OF ONE-FOURTH TO ARTHUR L. ZWISLER, OF KALAMAZOO, MICHIGAN, ONE-FOURTH TO MILES HEATH, OF DETROIT, MICHIGAN, AND ONE-FOURTH TO ELMER HEATH, OF ALBANY, NEW YORK.

SIGNAL DEVICE.

1,233,646.

Specification of Letters Patent. Patented July 17, 1917.

Application filed May 27, 1916. Serial No. 100,242.

To all whom it may concern:

Be it known that I, Don J. Cook, a citizen of the United States, residing at the city and county of Kalamazoo, State of Michigan, have invented certain new and useful Improvements in Signal Devices, of which the following is a specification.

This invention relates to improvements in signal devices.

10 My improved signal device is especially designed by me for use on motor vehicles for indicating contemplated turning or stopping of the vehicle or the like.

The main objects of this invention are:

15 First, to provide an improved signal device for motor vehicles and the like which is simple and compact in structure and very convenient to operate.

Second, to provide an improved signal device which is not likely to become inoperative or get out of repair.

20 Third, to provide an improved signal device which is also adapted to illuminate the license plate of the vehicle and constitute a tail lamp.

Further objects, and objects relating to structural details, will definitely appear from the detailed description to follow.

25 I accomplish the objects of my invention by the devices and means described in the following specification. The invention is clearly defined and pointed out in the claims.

30 A structure which is a preferred embodiment of my invention is clearly illustrated in the accompanying drawing, forming a part of this specification, in which:

Figure I is a detail rear view of a motor vehicle having my improved signal device mounted in operative position thereon.

40 Fig. II is a detail view showing the operating switch of my improved signal device mounted upon the steering post of the vehicle.

Fig. III is a vertical longitudinal section 45 through my improved signal device on a line corresponding to line 3-3 of Fig. IV.

Fig. IV is a horizontal section on a line corresponding to line 4-4 of Fig. III.

50 Fig. V is a perspective view of the frame on which the operative parts are mounted removed from the casing with the indicia

members in their normal unactuated position.

Fig. VI is a perspective view similar to that of Fig. V with one of the indicia members in its actuated position.

Fig. VII is a plan view of the blank from which the partition forming the indicia member compartment is made.

Fig. VIII is a rear view of the casing showing the arrangement of the bracket.

Fig. IX is a sectional view through the steering post on a line corresponding to line 9-9 of Fig. II, showing the arrangement of the actuating switch thereon.

Fig. X is a detail section on a line corresponding to line 10-10 of Fig. IX.

Fig. XI is a diagrammatic view showing the wiring.

In the drawing similar reference characters refer to similar parts throughout the several views, and the sectional views are taken looking in the direction of the little arrows at the ends of the section lines.

Referring to the drawing, the casing 1, 75 illustrated, is shaped like a box open at the top and provided with a flanged cover 2 fitting thereon. This casing is formed of thin sheet metal. The cover is retained by the screws 3.

Within this casing is a removable frame 80 on which the operative parts are mounted. This frame comprises a back plate 4, front corner uprights 5 connected to the back plate by the top cross pieces 6 and the bottom piece 7. This bottom piece 7 is formed integrally with the back plate. A top piece 8 extends between the cross pieces 6.

The bottom is provided with an opening 9 registering with an opening 10 in the 90 bottom of the casing (see Fig. III). These openings constitute an illuminating window opening so that the device may serve as a means for illuminating the license plate 11 which is mounted below the same, as 95 shown in Fig. I. The casing 1 is provided with an indicia or signal opening 12 (see Figs. I and IV).

To provide a compartment for the indicia slides 13, which are formed of transparent 100 material such as celluloid with the suitable indicia thereon such as Right, Left, and

Stop, as in the structure illustrated, I provide a partition plate 14 having a window opening 15 opposite the window opening 12 of the casing. This window opening 15 is closed by the panel 16 of celluloid or other suitable material, preferably colored red, so that the device serves as a tail light for the vehicle. This partition plate 14 is provided with forwardly projecting end portions 17 having flanged portions, constituting the corner uprights 5, and with a forwardly turned portion at the bottom constituting the bottom cross piece 18 of the frame. These parts are welded together so that they form a solid frame. These upright portions 5 have laterally turned feet 19 at their lower ends which lap upon and are welded to the bottom member of the frame.

To support the glass 20 at the rear of the window opening 12 of the casing the upright portions 5 are provided with forwardly projecting flanges 21 having in-turned rests 22 at their lower ends on which the glass 20 rests.

25. The indicia slides 13 are supported in groove-like ways 23 arranged in opposed pairs on the end members 17 of the indicia member compartment. These ways guide and support the indicia members so that they may be shifted vertically to bring them into position so that they are visible through the window in the casing and properly illuminated from the lamp 24 supported on the bracket 25 on the rear plate of the frame (see Figs. III and IV).

The indicia members are actuated by rock shafts 26, 27, and 28, which are supported in bearings 29 disposed at the ends of the frame, there being two of the rock shafts 40 at one end and one at the other. These rock shafts are provided with arms 30 having curved portions at their ends slidably engaged with the loops 31 on the lower edges of the indicia members so that when the rock shafts are actuated the indicia members are raised to operative position. The rock shafts are actuated by means of the electromagnets 32 which are mounted on brackets 33 on the rear plate of the frame.

50. The lever armatures 34 are pivoted at 35 and disposed with their swinging ends in operative relation to the arms 36 on the rock shafts, there being an electromagnet and armature for each rock shaft. The 55 indicia members rest normally on the buffer 45'.

With the parts thus arranged, the actuation of an electromagnet will actuate one of the indicia members. These electromagnets are controlled from the switch or control lever 37 which is shown in engagement with one of the contacts 38, it being the one which controls the stop indicia member. These contacts are carried by a plate 39 mounted by means of the clip 40 on the

steering post 41 so as to be conveniently accessible. The contacts are connected through the circuits 42 to the electromagnets. A battery 43 is shown in conventional form for supplying the current.

70. The lamp 24 is controlled by the switch 44. The device is supported by a bracket 45.

With the parts thus arranged, they are simple and economical in structure and conveniently assembled. A further advantage 75 is that the structure is durable and not likely to get out of repair.

I have illustrated and described my improvements in a simple and practical embodiment. I have not attempted to illustrate or describe various modifications and structural details which I contemplate as I believe the disclosure made will enable those skilled in the art to which my invention relates to embody or adapt the same as 80 conditions or taste may dictate.

Having thus described my invention, what I claim as new and desire to secure by Letters Patent, is:

1. In a signal device, the combination of 90 a casing having an indicia window opening in its front and an illuminating window opening in its bottom, a frame removably disposed in said casing and comprising a back plate, a bottom member having an opening registering with said illuminating window opening of said casing, front and transverse top pieces, and a vertical partition plate having a window opening in alignment with the indicia opening of said 95 casing and provided with forwardly projecting end and bottom portions, the end portions having outturned flanges constituting corner uprights, said uprights being provided with forwardly projecting flanges 100 having in-turned rests at the bottoms thereof adapted to support a glass for the indicia window opening, a glass arranged in said 105 glass supporting flanges, transparent panels arranged over said opening in said partition plate and said illuminating window opening in the bottom of said casing, an illuminating lamp, vertical indicia slide ways arranged side by side on the end portions of said partition plate, indicia slides 110 mounted for vertical movement in said ways, and means for actuating said slides.

2. In a signal device, the combination of 115 a casing having an indicia window opening in its front, a frame removably disposed in said casing and comprising a back plate, and a vertical partition plate having a window opening in alignment with the indicia opening of said casing and provided with forwardly projecting end and bottom 120 portions, the end portions having out-turned flanges constituting corner uprights, said uprights being provided with forwardly projecting flanges having in-turned rests 125 at the bottoms thereof adapted to sup- 130

port a glass for the indicia window opening, a glass arranged in said glass supporting flanges, a transparent panel arranged over said opening in said partition 5 plate, an illuminating lamp, vertical indicia slide ways arranged side by side on the end portions of said partition plate, indicia slides mounted for vertical movement in said ways, and means for actuating said 10 slides.

3. In a signal device, the combination of a casing having an indicia window opening in its front, a frame removably disposed in said casing and comprising a back plate, 15 and a vertical partition plate having a window opening in alinement with the indicia opening of said casing and provided with forwardly projecting end portions, the end portions having out-turned flanges constituting corner uprights, a transparent panel arranged over said opening in said partition plate, an illuminating lamp, vertical indicia slide ways arranged side by side on the end portions of said partition plate, indicia slides mounted for vertical movement in said ways, and means for actuating said 20 slides.

4. In a signal device, the combination of a casing having an indicia window opening 30 in its front and an illuminating window opening in its bottom, a frame removably disposed in said casing and comprising a back plate, a bottom member having an opening registering with said illuminating 35 window opening of said casing, and a vertical partition plate having a window opening in alinement with the indicia opening of said casing, transparent panels arranged over said opening in said partition plate 40 and said illuminating window opening in the bottom of said casing, an illuminating lamp mounted on said back plate, vertical indicia slide ways, indicia slides mounted for vertical movement in said ways, and 45 means for actuating said slides comprising electro-magnets mounted on said back plate.

5. In a signal device, the combination of a casing having an indicia window opening in its front, a frame removably disposed in 50 said casing and comprising a back plate, and a vertical partition plate having a window opening in alinement with the indicia opening of said casing, a transparent colored panel arranged over said opening in said 55 partition plate, an illuminating lamp mounted on said back plate, vertical slide ways, indicia slides mounted for vertical movement in said ways, and means for actuating said slides comprising electromagnets mount- 60 ed on said back plate.

6. In a signal device, the combination of a casing having an indicia window opening in its front, a frame removably disposed in 65 said casing and comprising a vertical plate having a window opening in alinement with

the indicia opening of said casing and provided with forwardly projecting end members, a transparent panel arranged over said opening in said partition plate, a lamp mounted on said frame, a series of vertical 70 indicia slide ways arranged side by side on the end portions of said partition plate, indicia slides mounted for vertical movement in said ways, rock shafts disposed transversely of said frame at the ends thereof, 75 and provided with arms projecting through said partition plate end members and having curved ends, loops disposed centrally on said indicia members and slidably engaging said arms, said rock shafts being provided with 80 actuating arms at their rear ends, a series of electromagnets mounted on said frame, and lever-like armatures pivotally mounted on said frame below said electromagnets to 85 coat with said actuating arms of said rock shafts.

7. In a signal device, the combination of a casing provided with an indicia window, a lamp within said casing, vertical indicia slide ways arranged side by side, indicia slides 90 mounted for vertical movement in said ways, rock shafts provided with arms having curved ends, loops disposed centrally on said indicia members and slidably engaging the curved end of said arms, said rock shafts 95 being also provided with actuating arms, electromagnets, pivotally mounted lever-like armatures coating with said actuating arms of said rock shafts, and a centrally disposed buffer and rest for said indicia slides. 100

8. In a signal device, the combination of a casing provided with an indicia window, a lamp within said casing, vertical indicia slide ways arranged side by side, indicia slides mounted for vertical movement in 105 said ways, rock shafts provided with arms having curved ends, loops disposed centrally on said indicia members and slidably engaging the curved end of said arms, said rock shafts being also provided with actuating arms, 110 electromagnets, and pivotally mounted lever-like armatures coating with said actuating arms of said rock shafts.

9. In a signal device, the combination of a casing provided with an indicia window, 115 a lamp within said casing, vertical indicia slide ways arranged side by side, indicia slides mounted for vertical movement in said ways, rock shafts provided with arms having curved ends, loops disposed centrally 120 on said indicia members and slidably engaging the curved end of said arms, said rock shafts being provided with actuating arms at their rear ends, electromagnets arranged at the rear of said slides, and armatures 125 coacting with said actuating arms of said rock shafts.

10. In a signal device, the combination of a casing provided with an indicia window, a lamp within said casing, vertical indicia 130

slide ways arranged side by side, indicia slides mounted for vertical movement in said ways, rock shafts connected to said indicia slides, said rock shafts being provided with 5 actuating arms at their rear ends, electro-magnets arranged at the rear of said slides, and armatures coacting with said actuating arms of said rock shafts.

In witness whereof, I have hereunto set my hand and seal in the presence of two 10 witnesses.

DON J. COOK. [L. s.]
